CLAIM

The ornamental design for a rechargeable battery pack, substantially as shown.

DESCRIPTION

FIG. 1 is a front elevational view of a rechargeable battery pack showing our new design;

FIG. 2 is a right side elevational view thereof;

FIG. 3 is a top plan view thereof;

FIG. 4 is a left side elevational view thereof;

FIG. 5 is a bottom plan view thereof;

FIG. 6 is a rear elevational view thereof; and

FIG. 7 is a rear perspective view thereof.
